DESIGN FOR A COCKTAIL RECIPE GUIDE

Louis F. Zimmermann, Chicago, Ill.

Application September 10, 1947, Serial No. 141,302

Term of patent 14 years

(Cl. D1—2)

To all whom it may concern:

Be it known that I, Louis F. Zimmermann, a citizen of the United States, residing at Chicago, in the county of Cook and State of Illinois, have invented a new, original, and ornamental Design for a Cocktail Recipe Guide, of which the following is a specification, reference being had to the accompanying drawing, forming part thereof.

Fig. 1 is a front view of a cocktail recipe guide showing my new design,

Fig. 2 is a rear view thereof, and

Fig. 3 is a top edge view thereof.

I claim:

The ornamental design for a cocktail recipe guide, substantially as shown.

LOUIS F. ZIMMERMANN.
